UNITED STATES PATENT OFFICE

CLAUD T. MILLER, OF HARVEY, ILLINOIS, ASSIGNOR TO THE BUDA COMPANY, OF HARVEY, ILLINOIS, A CORPORATION OF ILLINOIS

BUMPING POST

Application filed December 3, 1928. Serial No. 323,294.

This invention relates to railway bumping posts of the type adapted to be anchored to the rails of the track.

One of the primary purposes of the invention is to provide a bumping post which can be securely anchored to the track without drilling or otherwise perforating the track rails.

Another object is to provide a post capable of universal use so that it is applicable without change to rails of the various sizes and dimensions in common use in track construction.

A further object is to provide a bumping post which will be strong, substantial, and durable, one which can be economically manufactured, and which can be readily applied to the track rails with a minimum of effort and labor.

Still another object is the provision of a bumping post which can be readily assembled and is capable of application to rails, the inner edges of which may be spaced varying distances apart.

Other objects and advantages will be apparent as the same becomes better understood by reference to the following description when considered in connection with the accompanying drawings.

Fig. 1 is a plan view of a bumping post installation embodying my invention,

Fig. 2 is a side elevation of the same,

Fig. 3 is an enlarged fragmentary sectional view taken on the line 3-3 of Fig. 1,

Fig. 4 is an enlarged sectional view taken on the line 4-4 of Fig. 1 with parts omitted,

Fig. 5 is an enlarged sectional view taken on the line 5-5 of Fig. 1,

Fig. 6 is a similar view taken on the line 6-6 of Fig. 1,

Fig. 7 is a bottom view showing the underside of the means for attaching a rear leg of the post to a rail,

Fig. 8 is a similar view of a modified form, and

Fig. 9 is a similar view showing the attachment of a front leg.

Referring to the drawings more in detail, reference numerals 1 and 2 indicate the rails

of an ordinary track supported in the usual manner upon the ties 3.

The bumping post, which is designed to be anchored to the track, is generally designated by reference character 4 and comprises a pair of diverging rear legs 5 preferably of channel bar construction, secured by bolts or otherwise to the cast head 6 and equipped at their lower ends with shoes 7 and 8 respectively by which these legs are anchored.

The front legs which diverge downwardly and forwardly from the head of the post may be made of any preferred cross sectional shape, such as flat straps, square bars, or, as shown in the drawings, they may be round. The front legs are designated generally by reference character 9 and comprise two structurally independent bars or legs 11, each pivotally connected at its upper end to the head 6. This connection is effected by bending the upper ends of the legs inwardly and passing them through opposed openings in flanges 34 formed on the back of the head. The legs are connected to the head in any suitable manner such as by nuts threaded upon their inner upper ends, and preferably they are connected together to form a generally U-shaped structure by a turn buckle 33 threaded upon the opposed ends of the legs. The lower end of each leg is bent outwardly as indicated at 12 to extend beneath the track rail.

In order that the post may be securely anchored to the track rails without drilling or otherwise forming holes in the rails, my invention contemplates the provision of means for securely clamping the legs of the post to the track rails, and furthermore, in order to make the post universally adapted to rails of various sizes, the clamping means, which will be later explained more in detail, are constructed to engage and be securely anchored to the various sizes of rails commonly in use.

The clamping means for the rear legs 5 is shown in detail in Fig. 3 by reference to which it will be observed that the shoes 7 and 8 are respectively formed to provide outwardly opening tapered grooves 13 and 14 designed to accommodate and snugly grip the inwardly

extending flanges of the rail bases. Cooperating clamping members 15 and 16 provided with similarly shaped rail base receiving grooves 17 and 18 respectively are designed 5 to be drawn into clamping relation with the shoes by means of clamping bolts 19 passing through aligned openings in the respective shoes and clamping members.

As is most clearly apparent from Fig. 7, 10 each shoe is secured to its rail by four clamping bolts 19, two of which are associated with each of the blocks or flanges 21 extending beneath the rail. Two corresponding clamping members cooperate with each shoe, each 15 clamping member being designed to receive two of the clamping bolts 19. In order to provide a maximum bearing surface against the lower face of the rail and to prevent cramping of both the shoes and the clamping 20 members, the vertical faces of those portions 21 of the shoes which are disposed beneath the rails are inclined longitudinally of the rail and similarly the vertical opposed faces of those portions 22 of the clamps which are 25 disposed beneath the rails are inclined parallel with the opposed faces of the shoe. This construction gives a maximum bearing surface against the lower face of the rail and offsets with respect to each other the exposed 30 portions of each pair of clamping bolts so as to diminish the liability of their bending, to decrease the liability of cramping and to afford a maximum bearing surface against the rail.

35 The shoe is provided between its clamping members with an integral plate 25 extending beneath the rail and provided with apertures 26 outside the rail for the reception of spikes by which the plate may be secured to 40 the tie. These apertures have a stepped wall to enable the spikes to be driven close to the edge of the rail base, irrespective of the width of this base, which is dependent, of course, upon the size of the rail. The plate 45 25 is also provided at one edge with a downwardly extending flange 20 forming an abutment engaging one vertical face of the tie which also assists in holding the shoe against displacement longitudinally of the track. 50 Spike receiving openings 30 may also be provided inside the rail for further securing the shoe to the underlying tie.

In some cases, the plate 25 may be dispensed with, and this modification is illustrated in Fig. 8. In other respects, this construction is similar to that just described in connection with Fig. 7.

The impact of a car against the head of the bumping post will tend to spread the legs 60 5, and in order to strengthen the structure and overcome this spreading tendency, the shoes 7 and 8 may be formed to provide inward extensions 27 and 28 respectively, terminating in upwardly disposed lugs 29 and 65 31 adapted to receive a tie bolt 32, best shown

in Figs. 1 and 3, by which the shoes are rigidly connected together and held against separation.

The forward legs 11, as previously noted, are structurally independent from each other, thus facilitating the assembly of the post on the track. The laterally turned end 12 of each leg extends beneath the base of its rail and through an opening in the central portion 45 of the outer clamping member 35, nuts 46 being employed to prevent withdrawal of these ends. The clamping member 35 is provided on its inner face with a tapered groove 37 for the reception of the outer flange at the rail base and an inner clamping member 36 provided with a similar groove 38 is connected with and drawn toward the member 35 by clamping bolts 40. That portion 39 of the clamping member 36 which extends beneath the rail, has its vertical face 43 disposed at an incline to the longitudinal axis of the rail, and the opposed face 44 of the clamping member 35 is similarly inclined parallel to the face 43 so that maximum surface engagement with the bottom of the rail is provided and cramping of the clamping members is obviated in the same manner as previously explained in connection with the clamps for the rear legs.

90 The opposite end of the member 35 is secured to the rail, as will be apparent from Figs. 1, 5, and 9, by a bolt 50, cooperating with an opposed clamping member 41. The wide body portion 42 of the clamp 35 has an enlarged portion 45, as previously explained, for the reception of the end 12 of the front leg.

95 It will be apparent from the foregoing that both the front and rear legs of the post are securely anchored to the track rails by being clamped thereto and that movement of the legs longitudinally of the rails is precluded by the friction exerted upon the rails by the tapered grooves of the clamping members. One or more of the inner faces of these 100 grooves may, if preferred, be roughened to increase the clamping friction. The clamps shown and described for illustrative purposes are designed to engage the bases of the track rails, but obviously the clamps might be 105 designed if preferred to clamp just as securely to the heads of the rails instead. The tapered grooves which engage and clamp the rail adapt the device for attachment to the rails of various sizes, consequently my post may universally be used, and requires no change for anchorage to any size of rail, and may be removed from rails of one size and anchored to rails of another size without modification of the clamping members.

110 The impact of the car against the post which tends to spread the rear legs, similarly tends to draw the front legs together. To 115 overcome this tendency of the front legs to draw together, I have provided a spacer in 120 125

the form of a hollow pipe 47 extending between the clamping members 36, this pipe being of a length to just fit between the members 36 when the post is applied to rails of the largest size. A tie rod 48 extends through the spacer 47 and is anchored by nuts at each end thereof, indicated by 49. When the post is applied to rails of smaller sizes, the length of the spacer may be augmented by the application of the washers at the ends of the spacer. The rear legs are somewhat resilient, and while they are normally spaced apart at their lower ends to engage the smaller sized rails, they are capable of being sprung together sufficiently to compensate for rails of larger sizes. My post, therefore, is adaptable both with respect to the legs themselves and with respect to the means for attaching them to the rails to be employed without modification to rails of various sizes.

It is believed that my invention and many of its inherent advantages will be understood from the foregoing without further description and it should be manifest that the details of construction illustrated and described are capable of considerable modification without departing from the spirit of the invention as defined in the following claims.

I claim:

- 30 1. A railway bumping post comprising a head, rear legs rigidly secured thereto, front legs pivotally attached to said head, and means for anchoring said post to the rails of a track, including rail engaging clamps whereby each leg is rigidly anchored.
- 35 2. A railway bumping post comprising a head, a pair of diverging rear legs rigidly secured to the head, shoes carried by the rear legs provided with grooves each adapted to receive a portion of a track rail, clamping members provided with grooves adapted to receive the opposite portions of the rails, bolts extending transversely beneath the rails by which said shoes and clamping members are drawn together to firmly clamp the interposed rail, front legs attached to said head, and rail engaging clamps connected with said front legs whereby said legs are anchored to their respective track rails.
- 40 45 3. A railway bumping post comprising rear legs, each equipped at its lower end with a shoe having a tapered groove adapted to snugly embrace a portion of the track rail, means including a plurality of clamping members and bolts whereby said shoes are rigidly anchored to the rails, and an adjustable tie rod connecting said shoes to prevent spreading of the legs.
- 45 50 55 60 65 4. A railway bumping post comprising a pair of rear legs, shoes carried by the lower ends of said legs and provided with tapered rail receiving grooves, clamping members provided with rail receiving grooves, a plurality of bolts for drawing each of said clamping members into clamping relation

with its respective shoe, the opposed faces of those portions of the shoes and clamping members beneath the rails being disposed diagonally of the rails, and means connecting said shoes to prevent spreading movement of the legs.

5. A railway bumping post comprising a head, supporting legs therefor, and means for anchoring the lower ends of said legs to the rails of a track, said means including a shoe for each leg provided with a tapered rail flange receiving groove, a pair of clamping members cooperating with said shoe and provided with tapered rail flange receiving grooves, a plurality of bolts for drawing each clamping member toward its shoe to securely clamp the rail therebetween, the opposed portions of said shoe and clamping members beneath the rail being substantially triangular in shape with their opposed edges extending diagonally of the rail and said shoe being provided with a downwardly projecting abutment adapted to engage a vertical face of a tie.

6. A railway bumping post comprising legs, and means for anchoring said legs to a railway track, said means including opposed members provided with tapered grooves adapted to receive the oppositely extending flanges of a track rail, bolts for drawing said members together to firmly clamp the rail therebetween, a depending abutment for engaging the vertical face of a rail tie, and a plate disposed between the rail and the tie intermediate the clamping members, said plate being provided with spike receiving openings.

7. A railway bumping post comprising a head, rear legs rigidly secured to the head, means for anchoring said rear legs to a railway track, independently movable front legs attached to said head, and means for anchoring said front legs to the track rails, said means including an outer clamping member for each rail provided with an opening through which the laterally bent lower end of a front leg projects, a plurality of cooperating clamping members, means for drawing said clamping members together to firmly clamp the rail therebetween, a tie rod attached to the outer clamping members beneath the rails to prevent spreading of the rails, and a spacer extending between the opposite inner clamping members to prevent approaching movement of the rails.

8. A railway bumping post comprising a head, rear legs rigidly attached to the head, front legs pivotally connected with the head, outer rail clamping members to which said front legs are respectively attached, inner rail clamping members opposed to said outer members, bolts for drawing said clamping members together to rigidly clamp interposed track rails, means connecting the outer clamping members to prevent spreading of the rails,

and means disposed between the inner clamping members to oppose approaching movement of the rails.

9. A railway bumping post comprising front and rear legs, means including inner and outer clamping members and cooperating bolts for securely anchoring said legs to the track rails, said means being adapted for connection to rails of various sizes, means for preventing approaching movement of the rails adjacent the point of attachment of the front legs thereto, and means for preventing spreading movement of the rails adjacent the points of attachment of the front and rear legs thereto.

10. A railway bumping post comprising a head, diverging rear legs rigidly secured to said head, clamping means for securely anchoring said rear legs to track rails without perforating said rails, said rear legs being sufficiently yieldable to accommodate various rail spacings and said clamping means being adapted for connection to rails of various sizes, front legs comprising inwardly turned upper ends pivotally connected with the said head and outwardly turned lower ends disposed beneath the track rails, and means for anchoring said front legs to the track rails comprising outer clamping members to which the ends of said legs are connected, inner clamping members adapted to cooperate with said outer members to securely clamp the rails, clamping bolts adapted to securely clamp the members into engagement with the rails, said clamping members being adapted for connection to rails of various sizes, means cooperating with said outer clamping members to prevent spreading of the rails, and means cooperating with said inner clamping members to prevent approaching movement of the rails.

In witness of the foregoing I affix my signature.

CLAUD T. MILLER.
